VEHICLE TOWING APPARATUS OR THE LIKE

Augustus W. Whisnand, 37307 5th St. E., Palmdale, Calif. 93550; Glen C. Easterling, 40170 107th St. W., Leona Valley, Calif. 93550; and David H. Kipp, 38547 Sumac St., Palmdale, Calif. 93550

Filed May 21, 1968, Ser. No. 12,034

Term of patent 14 years

Int. Cl. D12—14, 99

U.S. Cl. D14—6

FIGURE 1 is a perspective view of a vehicle towing apparatus or the like embodying the new design; FIGURE 2 is a left side elevational view thereof; and

FIGURE 3 is a plan view thereof.

The cooperating portions of a towed vehicle shown in broken lines in FIGURE 2 are included for illustrative purposes only.

We claim:

The ornamental design for a vehicle towing apparatus or the like, substantially as shown and described.
